UNITED STATES PATENT OFFICE.

PHILIP D'HUC DRESSLER, OF CLEVELAND, OHIO. ASSIGNOR TO AMERICAN DRESSLER
TUNNEL KILNS, INC., OF CLEVELAND, OHIO, A CORPORATION OF NEW YORK.

OPEN-FIRE TUNNEL KILN.

Application filed March 24, 1921, Serial No. 455,062. Renewed July 11, 1924.

To all whom it may concern:

Be it known that I, PHILIP D'HUC DRESSLER, a subject of the King of Great Britain, and resident of Cleveland, in the county of Cuyahoga and State of Ohio, have invented certain new and useful Improvements in Open-Fire Tunnel Kilns, of which the following is a specification.

My present invention consists in improvements in the construction of, and method of operating a continuous open fire tunnel kiln for burning bricks and other ceramics and for other purposes for which tunnel kilns are or may be employed where the conditions are such as to permit the kiln to be heated by the flow of burning gases and hot products of combustion through the kiln chamber.

The general object of the present invention is to provide an open fired tunnel kiln construction and method of operating the same which will permit of the desired graduation in the kiln chamber temperature longitudinally of the kiln; while substantially minimizing temperature variations between points located at different vertical levels in any transverse vertical plane through the high temperature section of the kiln.

In a continuous tunnel kiln suitable for burning brick, with any reasonable efficiency and capacity, the kiln chamber must be of considerable length. For example, 300 feet may be assumed to be a typical length of kiln though such kilns are sometimes made shorter and are frequently made longer than this. With the assumed length of kiln chamber a portion of say 60 feet or so in length at the entrance end of the kiln forms a preheating zone, and a portion at the other end of the kiln of 100 feet in length or so forms the cooling zone, while an intermediate portion of 140 feet or so forms the heating up, furnace, or high temperature burning zone. The bricks to be burnt or other goods heated are moved through such a kiln on cars which are inserted in the entrance end of the kiln one at a time and are then slowly moved through the kiln chamber which is thus normally filled by a train of such cars, one car being removed at the exit end of the cooling zone of the kiln each time a car is inserted at the entrance end of the kiln. The

length of time required for the passage of a car through the kiln will depend on the character of the ware being treated and the conditions of operation, but in a kiln of the character referred to by way of example above, it would be in accordance with usual practice to make each car six feet long and to insert a car every hour or so so that each car would require something like 50 hours for its transit through the kiln. In a kiln of this character the desired mode of operation is one which will cause the bricks or the like passing through the kiln to gradually heat up from the temperature at which they enter the kiln to the maximum temperature to which they are subjected, and to then cool down more or less uniformly, to a temperature at which they may be safely discharged from the kiln into the atmosphere.

Now it is obviously desirable, to insure a uniform product, that the various bricks or other goods on each kiln car, whether located at the bottom or the top or at the sides or in the center of the pile of goods stacked on the car, be subjected not only to the same maximum firing temperature, but to substantially the same temperatures for substantially the same periods of time throughout the heating operation.

In a typical open fired kiln as heretofore constructed, burning gases or hot products of combustion or a mixture thereof are introduced into the kiln chamber along a comparatively short portion of the length of the high temperature or firing zone of the kiln adjacent the junction of that zone with the cooling zone, and are then drawn longitudinally of the kiln chamber toward the entrance end of the latter, being ordinarily withdrawn from the kiln chamber proper, at the junction of the burning and preheating zone, and then passed lengthwise of the preheating zone of the kiln through muffles at the sides of the kiln chamber or through heating flues formed in the walls of the kiln. The purpose of preventing heating gases from coming into contact with the bricks or other ware in the preheating zone of the kiln is to avoid discoloration and other injurious effects produced by such contact at low temperatures especially in the presence of moisture driven out of the ware.

When the heating gases are thus intro-

duced into the firing zone of the kiln, along a relatively restricted portion of the length of the latter, and their flow through a substantial portion of the burning zone is longitudinal, the temperature in the portion of the burning zone where the flow is mainly longitudinal tends to be much higher at the top of the kiln than at the bottom of the kiln owing to the natural tendency of the hotter gases to pass to the top of the kiln chamber. Many arrangements have been proposed and tried to cause the heating gases to flow back and forth through the path traversed by the goods and in particular to compel them to flow through the lower portions of this path, but none of these arrangements have been effective to prevent the top of the burning zone at its cooler end from being much hotter than the bottom in kilns in which there is any substantial longitudinal flow of the heating gases through the kiln chamber. In consequence it has been found necessary in tunnel kilns of this type to so concentrate the heat in the lower portion of the high temperature end of the burning zone that the lower layers of bricks or the like on the cars receive heat much more rapidly in passing through this zone of the kiln than do the upper layers of brick. The result of this is that the bricks or other ware at the bottom of a car are at a lower temperature than the ware at the top of the car during a considerable portion of their travel through the burning zone and are then heated up at a rapid rate, as the car carrying the ware moves through the final portion of the burning zone. With this mode of operation it is difficult to insure that the ware at the top and bottom of a car are subjected to the same maximum temperature, and impossible to cause the ware at the top and bottom of the car to heat up at the same rates as is desirable to insure a uniform product.

In proceeding in accordance with the present invention I introduce the heating gases into the burning zone of the kiln, not along a more or less restricted portion of the zone adjacent its high temperature end but along all or practically all of the length of the zone, and regulate the heating gases both as to temperature and volume so that they flow mainly in a vertical direction upward through the ware to the top of the kiln and in doing so heat the ware at the different levels to practically the same temperatures. Since with this mode of procedure the major portion of the heating is done by the gases in their upward flow through the brick it is unnecessary to make provisions for preventing the free longitudinal flow of partially spent heating gases through the clearance space between the roof of the kiln chamber and the tops of the stacks of ware on the cars. In some cases provisions may be made for withdrawing more or less of the heating gases from the top of the kiln chamber proper at intervals along the length of the burning zone, but ordinarily these gases need not be withdrawn from the kiln chamber until they are caused to pass out of the kiln chamber proper into the muffles or heating flues running alongside the preheating zone of the kiln.

By proceeding in accordance with the present invention the goods are subjected to a heat treatment analogous to that occurring in the well known up draft intermittent kiln wherein the temperature in the kiln is progressively increased throughout the period, usually of several days, required for a single burning operation. In the ordinary operation of such a kiln, as is well-known, the burning operation starts, with the kiln and its contents cold, by igniting a little kindling wood in the kiln furnace chambers, and then wood and finally coal or coke is added in small and carefully regulated amounts until a relatively high temperature is reached, after which the fuel is supplied freely until the maximum desired temperature is reached. With the present invention the draft is mainly upward throughout the firing zone as in the intermittent up draft kiln, and the temperature increases progressively along the length of the firing zone.

As compared with previous open fired kilns, the present invention is distinguished by the fact that the total quantity of heat which is supplied to the kiln is distributed along a greater portion of the length of the kiln. This reduces the danger of local overheating of the kiln structure.

The various features of novelty which characterize my invention are pointed out with particularity in the claims annexed to and forming a part of this specification. For a better understanding of the invention, however, and its advantages, reference should be had to the accompanying drawings and descriptive matter in which I have illustrated and described a preferred embodiment of the invention.

Of the drawings:

Fig. 1 is a diagrammatic plan with parts broken away and in section;

Fig. 2 is a partial sectional plan on a larger scale than Fig. 1;

Fig. 3 is an elevation in section on the line 3-3 of Fig. 2;

Figs. 4, 5, 6 and 7 are transverse sections taken on the lines 4-4, 5-5, 6-6, and 7-7, respectively, of Fig. 1;

Fig. 8 is a diagram illustrating temperature conditions prevailing in the kiln;

Fig. 9 is a diagrammatic elevation illustrating the circulation in the kiln;

Fig. 10 is a diagrammatic elevation illus-

trating the circulation in a prior type of open fire, intermittent kiln;

Fig. 11 is a diagram illustrating the temperature conditions in the kiln shown in Fig. 10; and

Fig. 12 is a diagrammatic elevation illustrating another prior type of open fired kiln.

The kiln construction shown in Figs. 1 to 7 inclusive comprises an elongated kiln chamber A divided into a preheating zone a, a firing zone b, and a cooling zone c. The bricks R or other goods to be heated are moved through the kiln on trucks C running on track rails R. The trucks C are formed in the usual manner with metallic frames and wheels and a refractory body portion. The refractory body portion is formed in its upper portion with transversely extending channels C' which are open at their outer ends to receive the heating gases and are open all the way along or at intervals along their top edges to permit the heating gases to pass upward into the spaces between the bricks or other goods mounted on the trucks. The bricks or other goods are loosely stacked or arranged in the usual manner to permit the heating gases to flow in more or less tortuous paths upward through them. The heating gases are admitted to the kiln chamber through orifices or nozzles E which discharge the gases in horizontal jets at the level of the open outer ends of the truck channels C' and the parts should be so proportioned and the pressures so regulated that the jet velocities will be such as to cause all or practically all of the heating gases delivered by the nozzles E to enter the channels C' and to pass the proper portion of the heating gases to the central portion of the trucks and the goods mounted thereon. In the illustration shown the nozzles E are distributed along the entire length of burning zone b. The ribs or partitions between the channels C' are advantageously tapered at their ends as shown at C². The heating gases may in some cases consist wholly or largely of combustible mixtures of air and gas which ignite and burn after admission to the truck channels C', or they may consist of hot but more or less completely burned products of combustion. In the particular construction shown the heating gases discharged through the nozzle members E are mainly hot products of combustion formed in the chambers D which are distributed along the opposite sides of the kiln and serve both as furnace chambers in which fuel is burnt, and as distributing flues for carrying the products of combustion from each fuel bed to a large number of nozzles E. In the particular construction shown each chamber D is provided at one end with a grate d supporting a fuel bed on to which coal or analogous solid fuel is passed from time to time. Valved steam

connections G from the steam supply pipe G' run to each grate D, and the steam thus supplied serves as is usual in furnaces of this type to reduce clinkering troubles and to induce the proper influx of primary air. Secondary air for the combustion of the combustible gases rising from the fuel beds are supplied to each chamber D through a corresponding inlet K' regulated by a damper K² from the corresponding secondary air supply main K of which, in the construction shown, there are two, one at each side of the kiln. Each combustion chamber D is provided with a fuel inlet door D' and an ash pit door D².

As shown the nozzles E are in the form of conical parts removably seated in the kiln wall and they may be made of the same refractory material as is commonly used in the gas burner nozzles of vertical flue coke ovens. Opposite each nozzle E an opening, normally closed by a refractory plug F, is advantageously formed in the outer wall of the corresponding chamber D. These openings permit inspection cleaning and replacement of the nozzles E. The number of combustion chambers D employed and their dimensions may vary quite widely, depending on conditions of use. As shown there are seven chambers D at each side of the kiln. The three chambers at the high temperature end of the firing zone are advantageously, though not necessarily, made shorter than the other chambers, and in one contemplated design of a kiln constructed in accordance with the present invention, the shorter chambers D are each about 15 feet in length, and the longer chambers each about 25 feet in length. It is to be understood that dimensions are given by way of illustration and not of limitation.

The secondary air supplied to the chambers D may advantageously be preheated, and this is accomplished with the construction shown by taking this air through outlets A¹⁰ from a series of hot air pockets which are open at their lower ends and extend along the top of cooling zone of the kiln, adjacent pockets being separated by transverse ribs or partitions A¹¹. The air passing out of the kilns through the outlet A¹⁰ enters a conduit or conduits I running along the roof of the cooling zone of the kiln to an exhaust fan J having branched outlets I' leading to the adjacent ends of the corresponding hot air ducts K.

Conduits are provided at the sides of the preheating zone of the kiln through which the heating gases are drawn from the adjacent end of the firing zone of the kiln and are passed to a suitable discharge stack Q. As shown these conduits comprise portions adjacent the junction of the preheating and firing zone which are formed of refractory tile sections L having open ended circula-

tion channels L' , such as are employed in the combustion chambers of the well-known Dressier kiln, whereby a directed convection current circulation of the kiln atmosphere 5 is maintained.

In the construction shown each of the two flues formed one at each side of the kiln, by the tile sections L , is connected at its end adjacent the entrance end of the 10 kiln to a series of conduits M which may be cast iron pipe. The pipes M at each side of the kiln are connected at the entrance end of the kiln to a corresponding junction box M' opening through its bottom wall to a 15 discharge passage O connected to an outlet flue O' . As shown the outlet flue O' leads to the inlet of an exhaust fan P , the outlet of which opens to the discharge stack Q .

20 With the construction illustrated, fuel and steam, and primary and secondary air are supplied to each combustion chamber as required to give the desired volume and temperature of heating gases. In general 25 the kiln temperature should vary longitudinally of the kiln as indicated by line TA in Fig. 8. With such a kiln temperature the temperature of the goods will be that generally indicated by the line T in Fig. 8. 30 With the described construction and mode of operation, it is comparatively easy, by properly proportioning the orifices in the nozzles E , and by regulating the supply of fuel, air and steam to the chambers D to 35 obtain a kiln chamber temperature closely approximating the ideal temperature indicated by the line TA in Fig. 8. With a kiln constructed and operating in accordance with the present invention the flow of the heating 40 gases throughout the entire length of the firing zone of the kiln will be generally upward as indicated by the arrows in Fig. 9 and by suitably regulating the amount and 45 temperature of the heating gases approximate uniformity in temperature at different levels in any plane, passing transversely to the length of the kiln through its firing zone may be obtained.

50 In this respect my present invention differs broadly from open fire continuous tunnel kilns as ordinarily heretofore constructed and operated in which burning gases or hot products of combustion are introduced into the kiln chamber through a comparatively short portion or portions of the length of the firing zone of the kiln. To better 55 differentiate the present invention from prior constructions, I have shown in Fig. 10 a diagrammatic representation of the general path of flow of the heating gases in an open fire tunnel kiln wherein the burning gases or hot products of combustion are introduced into the kiln chamber through an orifice e which is relatively short and is located at the hot end of the firing zone.

With such an arrangement the major portion of the heating gases will flow through the portion of the kiln indicated in Fig. 10 by the shaded area S , and the temperatures at points along the length of the kiln lying 70 within this shaded area will be appreciably above the temperatures of corresponding points along the length of the kiln outside the shaded areas. In consequence of such 75 temperature conditions when a stack of bricks is moved through the kiln, the bricks at the top of the stack will heat up much more quickly than will the bricks at the bottom of the stack, and will start to cool sooner than will the bricks at the bottom of the stack. The bricks at the bottom of the stack will be subjected to a marked and unduly rapid increase in temperature when the stack approaches the inlet orifice e . In 80 Fig. 11, T' indicates in a general way the 85 temperature variations of a brick at the top of the brick stack as it travels through the kiln, while T^2 represents the temperature variations of a brick at the bottom of the stack. When, as has sometimes been done, 90 a single furnace with a single inlet e is replaced by an arrangement in which there is a plurality of furnace inlets ea as illustrated in Fig. 12, the temperature conditions indicated by Fig. 11 are varied in degree only, 95 and not in kind, even though the orifices ea extend as they sometimes do along one-third or so of the length of the firing zone of the kiln.

The method of kiln heating and the apparatus which I have devised for carrying out this method make possible any desired graduation in the temperature gradient along the length of the firing zone of the kiln. With my invention it is easily possible to make the kiln atmosphere in any portion of the heating zone either oxidizing or reducing or neutral as conditions may require. Since with my invention the available heat in the heating gases is mainly abstracted from the gases during their vertical upflow through the kiln chamber there need be no substantial over heating of the top of the kiln with a corresponding tendency to over heat the goods adjacent the top of the kiln and an undue loss of heat by radiation from the top of the kiln. The use of my invention permits of a relatively simple and durable kiln structure.

While in accordance with the provisions of the statutes, I have illustrated and described the best form of my invention now known to me, it will be apparent to those skilled in the art that changes may be made in the form of the apparatus disclosed without departing from the spirit of my invention as set forth in the appended claims and that certain features of my invention may sometimes be used to advantage without the corresponding use of other features.

Having now described my invention, what I claim as new and desire to secure by Letters Patent, is:

1. The method of maintaining a graduated temperature along the length of an elongated heating zone of a tunnel kiln while minimizing temperature variations in any transverse plane through said zone which consists in introducing heating gases 10 into the kiln at the bottom of the pathway through the kiln for the goods along the length of said zone in such volume and at such temperatures and under such conditions of pressure and velocity that the heating gases thus introduced will flow mainly 15 upward through said pathway from the points of gas introduction to the top of the pathway, and will impart the major portion

of their available heat to the goods in their upward movement through the goods pathway.

2. In an open fire tunnel kiln comprising a preheating zone, an elongated heating zone, and a cooling zone, and heating flues along the preheating zone into which heating gases are drawn from the heating zone section of the kiln, the improvement which consists in provisions for passing heating gases into the lower portion of the kiln at distributed points along practically the entire length of the heating zone.

Signed at Cleveland, in the county of Cuyahoga and State of Ohio, this 16th day of March A. D. 1921.

PHILIP D'HUC DRESSLER.
